UNITED STATES PATENT OFFICE.

DAVID J. DAVIS, OF NEWARK, OHIO.

BRAN-PACKER.

SPECIFICATION forming part of Letters Patent No. 299,749, dated June 3, 1884.

Application filed September 17, 1883. (No model.)

To all whom it may concern:

Be it known that I, D. J. DAVIS, a citizen of the United States, residing at Newark, in the county of Licking and State of Ohio, have 5 invented certain new and useful Improvements in Bran-Packers; and I do declare the following to be a full, clear, and exact description of the invention, such as will enable others skilled in the art to which it appertains to make and to use the same, reference being had to the accompanying drawings, and to letters or figures of reference marked thereon, which form a part of this specification.

Figure 1 of the drawings is a representation 15 of a front elevation of my bran-packer. Fig. 2 is a rear elevation of the same. Fig. 3 is a vertical sectional view from front to rear, and Figs. 4, 5, and 6 are detail views.

This invention has relation to bran-packers 20 designed to pack square packages; and it consists in the construction and novel arrangement of devices, as will be hereinafter fully described, and particularly pointed out in the appended claims.

25 Referring by letter to the accompanying drawings, *a* designates the floor of the room in which the machine is built, and *b* is the ceiling of the room or floor of the upper room into which the studding of the frame of the 30 machine is mortised in the usual manner practiced in the construction of stationary machines.

c and *c'* are the two outer studs of the frame, which are connected near their upper ends 35 by two cross-beams, *d* *d'*, having a space, *d'*, between them.

e e e e designate four grooved studs, which 40 form guides for the piston-box *f*, which is rectangular in form and open at both ends. The front of this piston-box *f* is provided with a 45 rack-bar, *f'*, which engages a pinion, *f''*, on a horizontal shaft, *f'''*, having bearings in boxes *f^4* on the two front studs *e e*. This shaft *f'''* is provided with a ratchet, *g*, which engages a 50 pawl, *g'*, pivoted to the right-hand stud *e*. The shaft *f'''* is also provided with a hand-wheel, *g''*, by which it is operated to raise and lower the piston-box in the vertical ways formed by the grooved posts *e e e e*. The lower 55 edge of the piston-box *f* is provided with a rubber gasket, *g^3*, for a purpose hereinafter

explained. The rear wall of the piston-box *f* is provided near its top with an aperture, *h*, having inclined top and bottom edges.

i designates the piston, having rectangular 55 top and bottom plates or heads, *i i'*, perforated centrally for the reception of the power-screw *k*, and connected by four vertical strips of a length equal to the height of the piston-box *f*, so that the piston will completely fill the latter 60 when the piston is at its fullest extension downward. The power-screw *k* has its frictional bearing in the lower cross-beam, *d*, its friction-head *k'* resting on the upper face of said beam *d*, and its upper face bearing against the 65 under face of the cross-beam *d'*. Immediately beneath the cross-beam *d* the screw *k* is provided with a miter-gear, *l*, having the teeth on its lower face, said miter-gear *l* being rigidly keyed to said screw. Horizontal shafts 70 *m* and *m'*, a short distance below and one on each side of the miter-gear *l*, have their outer bearings in the studs *c c'* and their inner bearings in short pivoted bars *n n'*, the rear ends of which are pivoted in vertical slots *n^2* in the 75 rear studs *e e*, their free ends being permitted to work in vertical slots *n^3* in the front grooved studs *e e*, for a purpose hereinafter explained. The inner ends of the shafts *m m'* are provided with miter-gears, *p p'*, which are arranged to 80 be thrown in and out of gear with the miter-gear *l* by the following-described mechanism:

q q' designate two short arms pivoted in the slots *n^3* below the bars *n n'*, and to the inner ends of these short arms *q q'* are pivoted levers 85 *r r'*, which extend part way down the sides of the piston-box *f*. The tops of the sides of the piston-box *f* are kerfed or recessed vertically at *s s'*, and have recessed extensions *s^2 s^3*, in which are pivoted triggers *t t'*, to engage 90 the levers *r r'*.

u designates an adjustable bran-spout, through which the bran is delivered from the scale-hopper above the machine to the piston-box *f*, through the aperture *h* in the rear wall 95 of the latter. The adjustable portion *u'* of the bran-spout *u* is provided with a rack, *u^2*, in its rear face, which engages a spring-pawl, *u^3*, secured to the main spout, which is rigidly secured at its upper end to the ceiling *b*. The 100 lower end of the adjustable portion *u'* is bevelled from above down, and is provided at the

lower edge of the bevel with a central beveled projection, *w*, which enters the aperture *h* and holds the spout in place. *v* designates the packing-box, which is of the same size in cross-section as the piston-box *f*, and should be fifteen inches square to hold one hundred pounds of compressed bran. The box *v*, piston-box *f*, and piston may be enlarged in proportion to form square packages of two hundred pounds of compressed bran, if desired, without departing from the character of the invention. The packing-box *v* is provided with a door, *v'*, in front, and is provided also with half-staples *w* or slots in its top edges to receive the metal strap or wire *x*, by which the square-mouthed sack is held in place preparatory to shoving the packing-box under the piston-box. The sack is placed in the box and its mouth folded over the edges of the box, which is then placed under the piston-box, and the latter brought down upon it to hold the sack firmly in place. The gasket before mentioned prevents injury to the sack while under the strain resulting from compressing the bran into it. The short shafts *m m'* are provided with pulleys *z z'*, connected by bands to a single shaft, the belt connecting with the pulley *z'* being given a quarter-turn, to impart the necessary direction to the gearing on that side. The piston is run up in the piston-box by the gearing at the left-hand side of the machine, and the bran admitted to the piston box, through the bran-spout. The scale-beam of the scale-hopper should be near the piston-box to gage the number of pounds of bran delivered to the piston-box. The lever *r* at the right-hand side is pulled down, and a notch, *l*, in its inner face, is caught under the recessed projection 2, so that the inclined portion of the notch *l* will cover the recess in which the outer end of the trigger *t* now lies vertically. This will throw the gear-wheel *p* into engagement with the miter-gear *l*, which causes the power-screw *k* to force the piston down into the piston-box and compress the bran or ground feed into the packing-box beneath. The inner arm of the trigger *t*, when set by the lever *r*, is projected horizontally into the piston-box, and when the upper head of the piston reaches the trigger it strikes this arm, projects the other arm from its recess, and throws off the lever *r* from its catch and lets the gear *m* drop, thus stopping the downward motion of the piston in the piston-box. The trigger *t'* is arranged with its inner arm, *t'*, bent up instead of down, as in trigger *t*, and a spring, *t'*, is employed to hold it normally up. When set to move the piston up in the piston-box, the outer arm is turned up in its recess, compressing the spring *t'* therein, and the lever *r'* is pushed up, and the notch, which is the reverse of the notch in lever *r*, engages the top of the recessed projection and remains there until

the bottom of the piston strikes the trigger *t'* and throws the lever *r'* off the projection, when 65 the lever *r'* and its gear will drop down. The lever *r* will be next used, as before, to drive the piston down, and thus on throughout the operation of packing. After the requisite number of pounds have been compressed in 70 the sack, the piston is run up, the piston-box raised, the packing-box removed, (it is not, however, necessary to remove the packing-box,) the doors opened, and the sack taken out and closed ready for transportation. 75

The machine is quite simple, is not expensive, and does its work effectually and rapidly. The machine may be built for transportation, and may be put up in any suitable place.

It should be noticed that the two front 80 grooved studs *e e* are cut away near their lower ends to admit the packing-box to its place beneath the piston-box.

Having thus fully described my invention, what I claim as new, and desire to secure by 85 Letters Patent, is—

1. The combination, with the grooved studs *e e e*, of the piston-box *f*, working vertically therein and provided with a rack-bar, and a shaft having its bearings in boxes secured to the two front studs, *e e*, and provided with a pinion, pawl and ratchet, and a hand-wheel, substantially as specified.

2. The combination, with the power-screw *k*, having the miter-gear *l*, of the miter-gear *p* on the inner end of the shaft *m*, having its bearings in the post *c* and pivoted bar *n*, and the pivoted arm *q*, carrying the lever *r*, the trigger *t* in recess in the upper edge of the piston-box *f*, and the piston on said screw *k*, 100 substantially as specified.

3. The combination, with the piston-box *f*, having the trigger *t'*, the piston *i*, and the power-screw *k*, having the miter-gear *l* at its upper end, of the horizontal shaft *m'*, having 105 its bearings in the stud *c'*, and the pivoted bar *n'*, and the pivoted arm *q*, carrying the lever *r'*, substantially as specified.

4. In a bran-packer, the combination, with the piston-box *f*, having the aperture *h* in its rear wall near the top, of the adjustable bran-spout *u u'*, having the ratchet and spring-pawl, substantially as specified.

5. The packing-box *v*, of the same size in cross-section as the piston-box *f*, provided with a door, and having half-staples or top slots, in combination with the grooved studs *e e e* and the piston-box *f*, having a rubber gasket on its lower edge, substantially as specified.

In testimony whereof I affix my signature in presence of two witnesses.

DAVID J. DAVIS.
